UNITED STATES PATENT OFFICE.

AMBROSE H. WHITE, OF BROOKLYN, NEW YORK. ASSIGNOR TO INTERNATIONAL PAPER COMPANY, A CORPORATION OF NEW YORK

METHOD OF AND MEANS FOR DRYING PAPER.

Application filed May 11, 1923. Serial No. 638,221.

To all whom it may concern:

Be it known that I, AMBROSE H. WHITE, a citizen of the United States, residing at Brooklyn, in the county of Kings and State of New York, have invented certain new and useful Improvements in Methods of and Means for Drying Paper, of which the following is a specification, reference being had therein to the accompanying drawing.

This invention relates to the drying of paper in the course of its manufacture, and has reference more particularly to the drying of the paper web in its passage through the drying part of the paper making machine, which part consists usually of a number of hollow internally heated drying cylinders disposed in two series, one above the other, and arranged to receive the damp web from the "wet end" of the paper making machine, and over and around which cylinders the web travels and is subjected to a drying action, the said web being pressed against the cylinders in its travel therearound, by upper and lower bands or aprons known as "dryer felts". In the drying action of the cylinders on the paper web, the heat of the cylinders expels the moisture, and various expedients have been resorted to to get rid of this expelled moisture, as its presence in the room is very objectionable for many reasons, mainly, because of its reabsorption by the paper web; its collection on the dryer felts, more particularly on the upper stretch of the upper felt which is arranged over the cylinders and in the path of the stream of rising moisture-laden air; the intense heat created in the room; and the deposit of the moisture on the roof planking and other parts of the room. These objectionable conditions greatly retard the drying of the paper web, and they are the aim of my invention to overcome; and my invention consists of an improved method of expediting and facilitating the drying of the paper web, by subjecting the moisture-laden air as it rises from the paper, to a suction action applied above and adjacent the upper sides of the upper drying cylinders.

The invention consists also of a mechanism for carrying said method into effect, said mechanism being characterized by means arranged above the drying cylinders and acting to collect the moisture-laden

air rising therefrom, and a suction fan or apparatus adapted to draw off the collected air.

In the accompanying drawings:

Fig. 1 is a side elevation of the drying portion of a paper making machine, provided with means for carrying my improved method into effect, certain parts being broken away to better illustrate the construction.

Fig. 2 is an end elevation of the same on a reduced scale.

Fig. 3 is a top plan view of the same.

Fig. 4 is a perspective view on an enlarged scale, looking from beneath, of one of the members for collecting the moisture-laden air.

Fig. 5 is a side elevation of the same, partly in section.

Fig. 6 is a cross section on the line 6—6 of Fig. 5.

Referring to the drawings:

As shown more particularly in Fig. 1 the drying part of the paper making machine consists as usual of an upper series of drying cylinders 1, 1^a, 1^b, etc., and a lower series of drying cylinders 2, 2^a, 2^b, etc., which cylinders are internally heated and are mounted for rotation in a suitable frame 3, with the cylinders of one series disposed opposite the spaces between the cylinders of the other series. The damp paper web 4 from the wet end of the paper making machine, passes around the cylinders of the two series, the web being pressed against the lower sides of the cylinders of the lower series by means of a lower endless dryer felt 5 suitably supported and guided as usual; and being pressed against the upper sides of the cylinders of the upper series by means of an upper endless dryer felt 6 whose lower stretch is guided by guide rolls 7 situated between the cylinders, and whose upper stretch is guided above the cylinders by guide rolls 8 mounted on the frame of the machine some distance above the cylinders as clearly shown. The above described mechanism is one commonly employed to subject the damp paper web to a drying action, and the cylinders being rotated, the web will travel back and forth around and between the cylinders of the two series, said web passing downwardly from the inner side of one of the two ad-

5 jacent cylinders of the upper series, then around the opposing cylinder of the lower series, and up around the inner side of the other adjacent cylinder of the upper series, the heat of the cylinders acting to expel the moisture from the damp web, which moisture mixing with the air rises in the form of moisture-laden air.

10 In carrying my improved method into effect in connection with an apparatus of this form, I provide means above the respective cylinders of the upper series, for collecting the moisture-laden air rising from the paper in the drying action, which means in the 15 present instance is in the form of hollow sheet metal members 9, 9, 9, etc., extending lengthwise of the cylinders and concaved on their under sides so as to form in effect a series of domes open at their under sides 20 and closed at their ends by end walls 9^a. These domes are supported from the frame of the machine in horizontal positions over the respective cylinders, by brackets 10 fixed respectively to the framing and to the rear 25 walls of the domes, and they extend at their front and rear ends some distance beyond the ends of the respective cylinders as clearly shown in Fig. 2. The adjacent edges of the domes are preferably connected to 30 each other so that they conjointly form a number of collecting domes disposed above the respective cylinders and communicating with the common space immediately over the cylinders. As a result of this arrangement 35 and disposition of the parts, the moisture-laden air rising from the paper on the cylinders will enter and be collected by the domes at a number of points corresponding to the location of the cylinders, the tendency 40 of the heated air to rise causing the same to accumulate in the domes rather than to escape and flow laterally beyond the same.

45 The moisture-laden air thus collected, is, in accordance with my invention, continuously drawn off from the domes by subjecting the air in the domes to a suction or exhaust action. In the present instance this is effected by means of pipes 11, 11, which extend into the domes, one pipe for each 50 dome, which pipes are provided in opposite sides with perforations 12 for the entrance of the air from the domes. The pipes extend throughout the length of the domes and leave at their forward ends and extend upwardly and connect with a trunk pipe 13 extending transversely at the front of and above the series of cylinders. A pipe 14 extends rearwardly from the trunk pipe and is connected at its rear end with the intake side 55 of a suction or exhaust fan 15, by means of which the moisture-laden air collecting in the several domes is subjected to a suction action and is continuously drawn off from the domes. In this way the moisture and steam expelled from the paper in the dry-

ing action of the same is instantly removed from the machine and carried away, and is therefore prevented from being reabsorbed by the paper web or from collecting or accumulating on any of the parts of the machine or room.

60 It will be observed that the air collecting domes are situated beneath the upper stretch of the upper dryer felt, and therefore the latter is effectually protected from the accumulation of moisture on the felt, which moisture is carried by the upwardly flowing heated air, immediately into the collecting domes and is continuously abstracted therefrom.

65 The apparatus is of extreme simplicity and comprises but few parts, while it is effective and direct in its action in continuously and instantaneously removing from the machine and room, the heated moisture-laden air resulting from the drying action of the drying cylinders on the damp paper web.

70 In the foregoing description and accompanying drawings I have set forth my invention both in respect to the method of procedure and apparatus employed in the form which I prefer to adopt, and which in practise has been found to answer to a satisfactory degree the ends to be attained. It will be manifest however, that the invention 75 is not to be limited in respect to the method of procedure or details of the apparatus, except in so far as such limitations are specified in the claims.

75 Having thus described my invention, what I claim is:

1. The method of drying paper in paper making machines in which the paper passes over drying cylinders, which method consists in subjecting the moisture-laden air as it 80 rises from the paper, to separate and distinct suction actions applied adjacent the drying cylinders respectively, in a common space above said cylinders.

2. The method of drying paper in paper 85 making machines in which the paper passes over drying cylinders, which method consists in subjecting the moisture-laden air rising from the paper, to separate and distinct suction actions applied at points above 90 the respective cylinders in a common space above said cylinders.

3. The method of drying paper in paper 95 making machines in which the paper passes over drying cylinders, which method consists in collecting the moisture-laden air from a common space above said cylinders and at separate and distinct points adjacent to and above the respective cylinders, and drawing off the collected air at such points.

4. The method of drying paper in paper 100 making machines in which the paper passes over drying cylinders, which method consists in collecting the moisture-laden air from a common space above said cylinders 105

tive cylinders, and subjecting the collected air to a suction action to draw the same away.

5. In an apparatus for drying paper, the combination of a series of drying cylinders over which the paper to be dried passes, means over the respective cylinders for collecting at separate and distinct points the moisture-laden air rising from the paper, and means for drawing off the collected air.

6. In an apparatus for drying paper, the combination of a series of drying cylinders over which the paper to be dried passes, collecting domes over the respective cylinders to receive the moisture-laden air rising from the paper, and suction means acting to draw the air from the domes.

7. In an apparatus for drying paper, the combination of a series of drying cylinders over which the paper to be dried passes, collecting domes above the respective cylinders for collecting the moisture-laden air rising from the paper, a suction apparatus, and pipes connecting the suction apparatus with the respective collecting domes.

8. In an apparatus for drying paper, the combination of a series of drying cylinders over which the paper to be dried passes, collecting domes arranged above the respective cylinders and connected together at their adjacent edges, and means for drawing off the collected air from said domes.

9. In an apparatus for drying paper, the combination of a series of drying cylinders over which the paper to be dried passes, a series of air collecting members arranged over the respective cylinders and concaved on their under sides, pipes extending into said members and formed with openings for the admission of the collected air, and a suction apparatus connected to the pipes for drawing off the moisture-laden air.

10. In an apparatus for drying paper, the

combination of a series of drying cylinders over which the paper to be dried passes, a series of air collecting members arranged over the respective cylinders and concaved on their under sides, pipes extending in said members and provided on opposite sides with openings for the admission of the collected air, and a suction apparatus connected with said pipes.

11. In an apparatus for drying paper, the combination of a series of drying cylinders over which the paper to be dried passes, a series of air collecting members arranged over the respective cylinders, a trunk pipe extending transversely of the cylinders, a suction apparatus connected to said trunk pipe, and pipes leading from the trunk pipe and connected with the respective collecting members.

12. In an apparatus for drying paper, the combination of drying cylinders over which the paper to be dried passes, a dryer felt for pressing the paper on the drying cylinders, dryer felt guides for supporting the upper stretch of the felt above the cylinders, means between said upper stretch of the felt and the cylinders for collecting the moisture-laden air rising from the paper, and means for drawing off the collected air.

13. In an apparatus for drying paper, the combination of drying cylinders over which the paper to be dried passes, and endless dryer felt whose lower stretch acts to press the paper on the cylinders, means for guiding the upper stretch of the felt above the cylinders, means arranged between the cylinders and upper stretch of the felt for collecting the moisture-laden air rising from the paper, and suction means for drawing off the collected air.

In testimony whereof, I have affixed my signature hereto.

AMBROSE H. WHITE.
